UNITED STATES PATENT OFFICE.

BERNARD E. ROESSLING, OF PHILADELPHIA, PENNSYLVANIA, ASSIGNOR TO
FRANCIS J. MANEELEY, OF PHILADELPHIA, PENNSYLVANIA.

WALKING TOY.

Application filed August 24, 1920. Serial No. 405,685.

To all whom it may concern:

Be it known that I, BERNARD E. ROESSLING, a citizen of the United States, residing at Philadelphia, in the county of Philadelphia and State of Pennsylvania, have invented 5 certain new and useful Improvements in Walking Toys, of which the following is a specification.

This device is designed to simulate the 10 movements of a living creature, especially a bear, walking on two legs. The figure is held by its upper part, the head, shoulder or front paw, and, as it moves along the hind legs will simulate the movements of the legs 15 of the animal. The bear has its joints somewhat similar to the human leg; it is a plantigrade; and on account of the caricature of human movement presented by a bear walking on its hind legs, the movements of the 20 walking figure are very natural and at the same time comical.

Fig. 1 is a side view of the toy. Fig. 2 is a side elevation of the mechanical structure of the same. Fig. 3 is a detail view 25 of the parts forming the hip joint. Fig. 4 is a view of a modified hip joint construction. Fig. 5 shows the skeleton of the hip piece, shoulder and connecting rod.

The toy has a stuffed body and head and 30 forelegs, which are kept in position by a rod 3 extending from the hip piece 5 to the shoulder piece 1, consisting of a cross bar that has its ends extending close to the cover at the shoulders 2, and which is secured to the up- 35 right piece 3, which fixes the position of the shoulders 2 and the forelegs 4 and gives a sufficient rigidity to the body of the toy to enable the child playing with it to make it walk by taking hold of the arm or shoulder.

40 The hip piece 5 is of rigid material. It is provided with the extension 6, which may be of a yielding material, if desired, and enables the toy to take a sitting position as will be described below. The extension 6, projects downward from the main part of the 45 hip piece sufficient to cause the body of the toy to sit erectly, the body being supported by the extension 6, and the back of the upper leg portion, 9. These latter are connected at 50 the edges of these bevelled upper rods to the edge of the downwardly projecting bevelled portion of the hip portion. The centre of gravity of the body when the toy is seated lies between this extension 6, and the 55 joint between the upper leg portion and the

hip piece but much nearer the latter. This permits the body, when the toy is "seated" to be rocked forward, until it is stopped by the contact of the front incline of the downwardly projecting bevelled part of the hip 60 piece. The rod 3 can be screwed into the hip piece 5. If this rod be of metal, and the piece 5 and bar 1 of wood the connection between them can be very simply and cheaply made. 65

The hind leg pieces 9 and 8 that form the upper and lower portions of the legs respectively are made substantially rigid, so as to keep them firm and give proper support to the operating devices connecting them to 70 each other and to the hip piece 5. The hind feet should be made also rigid, so that the full effect of walking be given, as the rolling action in these feet forms a part of the operation of the device. 75

The joint between the hip piece 5 and the upper hind leg (piece 9) of the toy is a leaf hinge having one leaf attached to one of these parts and pressing against but free from the other. As shown the leaf 10 is secured to the inclined top 14 of the upper piece 9 of the hind leg, and the spring 12 pushes outward the leaf 11 into contact with the under side 13 of the piece 5. The inclined top 14 of the upper portion 9 of the 85 hind leg and the inclined portion 13 of the hip piece 5 are so arranged that the spring will lift slightly the piece 9 if free but can be compressed readily by the slight friction of the foot on the ground. The inclined 90 lower end 15 of the piece 9 and the inclined upper end of the piece 8 are arranged to allow the bending at the knee. These two parts are connected by the spiral springs 16, that tend to hold the two pieces 9 and 8 in 95 alignment.

The covering upon the toy can be made to simulate the hairy skin of a bear and be stuffed out to take the bear's shape. This cover can also serve to limit the movements 100 of the parts. For instance, the forward movement of the part 9 is limited by the portion of the cover between the extension and the part 9, and a possible reversed bending at the knees is prevented by the portion 105 of the cover covering their back portions. A somewhat like result can be obtained by the covering and rear portion of the knees. This cover fits tightly upon the thigh pieces 9 and the shin pieces 8. 110

The joint at the hips can also be made by using a pair of spiral springs 17, 17, in each leg as shown in Fig. 4.

The toy walks by tilting it slightly side-
5 wise, throwing the weight chiefly upon one leg and moving it forward. The hip spring will then throw the other leg slightly forward inclining the thigh more forward and letting the lower leg and foot drop a little,
10 thus advancing the leg and giving a close semblance to the waddle of a bear. The other leg is held meanwhile back by the friction of the foot on the ground. As the toy is moved further forward, the weight of the
15 toy will bring the lifted foot to the ground and the springs 16 will straighten the legs. The springs can be made so that they will bend under the weight of the lower leg and foot but yet straighten the leg when the leg
20 is under the body (as above described) and this will relieve the other leg of the body weight, which will have compressed its hip spring considerably and throw the leg forward. This action will be repeated and an
25 excellent simulation of the waddling walk of a bear will be produced. When the toy is to sit the projection and the lower side of the parts 9 will rest on the supporting surface.

I claim:

1. The combination in a walking toy of a 30 hip piece, an upright rod secured to the hip piece, a shoulder piece substantially at right angles to said upright rod and secured to same, leg pieces jointed to said hip piece and at the knees and having springs operating at 35 said hip portions and said knees, and a cover, provided with stuffing at the body portions filling out the shape of the toy and covering the leg portions, but fitting tight to the leg portions on either side of each joint and limiting the amount of turning permitted at each joint, said cover having stuffed front leg portions at the ends of the shoulder pieces. 40

2. The combination in a walking toy with 45 a vertical rod and shoulder piece substantially at right angles with said rod, of a hip piece secured to said vertical rod and having two projections, one of which is bevelled and has a horizontal edge, upper and lower leg 50 pieces jointed and springing at the knees, the upper ends of each upper leg piece being bevelled, said upper leg pieces being jointed along the edge of the bevel to the lower edge of the downwardly projecting bevelled portion of the hip piece. 55

In testimony whereof I affix my signature.

BERNARD E. ROESSLING.
